WELDER'S MASK

Kaiser W. Mentetski, Chicago, Ill.

Application April 2, 1937, Serial No. 134,479

11 Claims. (Cl. 2-8)

This invention relates to improvements in welders' masks and it consists of the matters hereinafter described and more particularly pointed out in the appended claims.

5 One of the objects of the present invention is to provide a mask especially adapted for use by operators of electric welding apparatus, gas welding and cutting apparatus and grinding wheels and the like, for affording a safe protection for the head and neck of the operator, against sparks and other flying particles encountered in work of this kind.

Another object of the invention is to provide a mask of this kind which may be adjusted according to the facial features of an operator to provide an accurate and comfortable fit of the mask so as to remain in place regardless of the position of the head, thus leaving both hands free for the work to be done.

20 A further object of the invention is to provide a mask of this kind which includes a sight opening covered by a ray filter to shield the eyes against harmful rays generated in welding and which ray filter may be made to uncover said sight opening for a clear vision therethrough, by a movement of the chin.

Still another object of the invention is to provide a mask of this kind including a chin actuatable means for operating the ray filter to uncover the sight opening for a clearer vision therethrough and which means is capable of being adjusted upwardly or downwardly and inwardly and outwardly to fit the head of the wearer regardless of the relative disposition of the facial features.

35 Still a further object of the invention is to provide a mask of this kind which, after having been once adjusted for an operator, may be quickly removed and then replaced without disturbing the adjustments of the various parts.

Again, it is an object of the invention to provide a mask of this kind wherein the parts are so disposed that it is possible to assemble said parts on a front plate of the mask for future attachment to the associated hood of the mask.

The above mentioned objects of the invention, as well as others, together with the advantages thereof will more fully appear as the specification proceeds.

50 In the drawings:

Fig. 1 is a view in front elevation of a welder's mask embodying the preferred form of the invention.

Fig. 2 is a view in side elevation of the improved mask.

Fig. 3 is a vertical sectional view through the mask on an enlarged scale as taken on the line 3-3 of Fig. 1.

Fig. 4 is a horizontal sectional view through the mask on the scale of Fig. 3, as taken on the line 4-4 of Fig. 1.

Fig. 5 is a vertical detail sectional view through a part of the mask as taken on the line 5-5 of Fig. 3.

Fig. 6 is a transverse detail sectional view on an enlarged scale through a certain extensible bar embodied in the mask as taken on the line 6-6 of Fig. 3.

Fig. 7 is a longitudinal sectional view through the extensible bar shown in Fig. 6 as taken on the line 7-7 of Fig. 6.

Referring now in detail to that embodiment of the invention illustrated in the drawings, 10 indicates as a whole, that part of the mask adapted to be worn upon the head of the person using the same. As herein shown, said member is in the form of a conventional welder's hood, made of a light weight, fireproof material, such as pressed fibre. The hood, which is of such vertical length as to protect the neck of the wearer, includes a front wall 11, side walls 12-12 and a top wall 13. In the top rear end of the hood is a forehead engaging rest 14 and associated with this part of the hood is a stall or head strap 15 by which the hood is secured in place upon the head. The hood thus far described may be taken as conventional for the welders' hoods such as are now used.

In the front wall of the hood is an opening 16 covered by a front plate 17. Bolts 18 pass through the marginal part of the front plate and through those margins of the front wall defining the opening 16. Nuts are applied to said bolts from the inside of the hood whereby the front plate is detachably secured to the hood. The front plate carries a flange 19 for engagement against the edge of the opening 16 and this materially assists in locating or positioning the front plate with respect to hood in the assembly of the mask as a whole.

The front plate includes a forwardly extending, hollow projection 20 of rectangular outline across the top thereof and a forwardly extending, hollow rib 21 arranged in the median line of the front plate below the projection 20. Said rib is formed with a bulge 22 to be grasped as a hand hold in applying and removing the mask.

The hollow projection 20 has top, bottom and side walls 23, 24 and 25-25 respectively that taper toward a framelike flange 26 so as to de-

55

45

35

40

45

50

fine a sight opening 27. The front side of said opening is normally closed by a transparent element 28 which seats against a gasket 29 on the flange 26. This element is preferably a piece of clear glass. In the use of the mask, this glass is bombarded by sparks, pieces of scale and the like and often a filament-like deposit adheres to the glass so as to impair the vision therethrough. Thus its use is limited as to time because such sparks often pit the same and the deposits before mentioned cannot be removed. Therefore, when the glass reaches a condition wherein visibility is materially reduced, it is removed and discarded and a new one is substituted therefor.

To make this an easy matter, I provide a frame 30 to receive the glass and hold it against the gasket 29. This frame which is of an angle bar cross section is removably secured in place by hooks 31-31 that engage the side portions of the frame. Each hook is carried on one end of a stem 32, the other end of which is yieldably and extensibly engaged in a hollow arm 33 that is pivoted at 34 between the ears of a pair of ears 35 secured to the side walls 25 of the hollow projection 20. The hooks 31 are arranged to engage behind suitable projections on the frame, as best appears in Fig. 4. To remove a glass, the hooks 31 are pulled outwardly and then the stems 32 are swung about the pivots 34. This permits removal of the frame 30 from which the used glass is removed for the substitution of a new one. The frame is now replaced upon the flange 26 and the hooks 31 swung back into the position shown in Fig. 4, to secure the frame in position.

Associated with the inner end of the sight opening 27 within the hollow projections 20 is a ray filtering means which normally covers this end of the opening. Said means preferably consists of a piece of glass 36 capable of filtering out the harmful rays in an electric arc or in a gas flame. It is preferably mounted between front and rear frames 37-38, the front frame being pivotally mounted along its bottom edge in the side walls 25 of the hollow projection 20 as at 39-39. Both frames are of an angle bar cross section and the rear frame 38 fits and is removably secured within the front frame. To provide the removable feature, the side portions of the front frame carry clamp screws 40 (see Fig. 4) for clamping engagement against side portions of the rear frame. A gasket 41 is interposed between the ray filter 36 and the frame 38 and a second gasket 42 is secured to the flange 26 about the sight opening 27 for engagement by the front frame 37.

It is apparent that the parts providing the ray filtering means are pivotally mounted for an inward and downward swinging movement about the pivots 39-39 from a position normally covering the sight opening to one uncovering said sight opening. A stop 43 is provided on the inside of the hood to limit the downward swinging movement of the ray filtering means as a whole. This stop is supported by somewhat yieldable arms 44 that straddle that part of the opening 16 in the front wall of the hood, associated with the top end portion of the hollow rib 21 of the front plate.

The ray filtering means is held in its normal position covering the sight opening 27 by the following means: Arranged within the upper portion of the hollow rib 21 is a normally extensible plunger means indicated as a whole at 45 in Fig. 3. Said means includes a bottom plunger

portion 46 that is pivoted at its bottom end on a pin 47 secured in the opposite sides of the hollow rib at this point. The top end of said plunger extends into the bottom end of a tubular sleeve 48. One end of a link 49 is pivoted to the top end of the sleeve 48 as at 50 and the other end of said link is pivoted to an arm 51 on the bottom edge of the frame 37 before mentioned. An expansible spring 52 is provided in the sleeve 48 between the plunger 46 and a cross pin 53 carried by the sleeve 48 below the pivot pin 50. The expansive action of said spring, operating through the sleeve 48 and link 49, normally urges the ray filtering means into a position covering the rear end of the sight opening 27.

A bell crank lever 54 which includes long and short arms 55-56 as best shown in Fig. 3 is pivoted on a pin 57. This pin is supported by ears 58 projecting upwardly from the bottom wall 24 of the hollow projections on each side of the space between the side walls of the hollow rib 21. The free end of the arm 55 is operatively engaged with the pivot pin 50.

When a force is applied to the arm 56 to swing the bell crank lever in a counterclockwise direction, as shown in Fig. 3, this actuates the sleeve 48 to compress the spring 52. This causes the arm 55 to pull downwardly on the link 49 and through the arm 51, swing the ray filtering means downwardly and inwardly to be stopped by its engagement with the member 43. In this position of the ray filtering means, a clear vision is had through the sight opening and through the glass 28. In this movement of the parts, the means 45 swings slightly inwardly about the pin 47. When the force before mentioned is released, the spring 52 operates to return the ray filtering means to its position covering the sight opening.

It is preferred that the force before mentioned for thus actuating the ray filtering means for uncovering the sight opening be afforded by movement of some facial feature or part of the operator. As the chin is capable of the desired amount of movement whereby the ray filtering means may be thus actuated, a chin engageable member 59 is provided. This chin engageable member which is concaved or cup shaped, is mounted on the hollow head 60 on one end of an extensible and contractible actuating bar indicated as a whole as at 61. This bar includes inner and outer telescopic sleeves 62-63, one end of the sleeve 62 being connected to the head 60 and the opposite end of the sleeve 63 being pivotally connected as at 64 to the arm 56 of the bell crank lever 54 before mentioned.

Associated with the actuating bar is an extensible and contractible fulcrum bar indicated as a whole at 65. The fulcrum bar, which is somewhat similar in construction to the actuating bar, includes inner and outer telescopic sleeves 66 and 67 respectively. To prevent the complete separation of the sleeves, in the extension of said sleeves, the sleeve 67 carries a spring catch 68. This catch has a bent end finger to extend through an opening in the sleeve 67 so as to slide along the sleeve 66. In the inner end of said sleeve 66 is a hole 69. In the extension of said sleeves, when said hole 69 registers with the finger of the catch, said finger drops into said hole to limit the separation between said sleeves. If it is desired to provide complete separation between said sleeve parts for cleaning or the like, the spring latch 68 is sprung away from the sleeve 66 to permit its withdrawal from

the sleeve 67. One end of the sleeve 67 is pivotally mounted on the pin 47 before mentioned. The opposite end of the sleeve 66 is enlarged to provide a head 70 arranged within the head 60 and having a pivotal connection therewith by means of a pin 71.

The actuating bar 61 is held in the desired extended condition by the following means. In one end of the inner sleeve 62 thereof is formed a cam surface 72 with which a rolling wedge 73 cooperates. This wedge has a peripheral portion that extends through a slot 74 in the sleeve 62 to grip against the internal surface of the sleeve 63. A spring 75 is disposed between said rolling wedge and a cross pin 76 in the sleeve 62 and this spring normally tends to move the wedge up the surface 72 so as to grip against the sleeve 63. To release the grip of the wedge when desired, a U shaped clevis 77 is so arranged that its closed end engages behind the rolling wedge and its open end is connected to one of an actuating link 78. The other end of this link is pivotally connected to an arm 79 of a trigger 80 that is also pivoted on the pin 71 before mentioned. When the trigger 80 is moved forwardly, this exerts a pull on the link 78 which through the clevis 77 moves the rolling wedge down the cam surface 72 to release its grip on the sleeve 63. In this position of the wedge, the sleeves 62-63 may be telescoped relatively to increase or decrease the length of the bar 61 as a whole. When the pressure on the trigger 80 is released, the spring 75 operates immediately to move the rolling wedge 73 up the cam surface 72 to again grip the sleeve 63.

It is apparent from the foregoing, that while the wedge 73 and associated parts form a one-way clutch which normally holds the actuating bar against extension or lengthening until the trigger 80 is actuated, the bar is capable of retraction or shortening without actuation of the trigger.

The fulcrum bar includes a two way clutch mechanism for holding the same against either extension or retraction but which clutch mechanism is capable of being actuated to permit such extension or retraction when necessary. Such mechanism is constituted as follows: In the inner end of the inner sleeve 66 is formed 45 opposed cam surfaces 81-81a, with each of which a rolling wedge 82-82a cooperates. These wedges have peripheral portions which extend through slots 83-83a in the top side of the sleeve 66 so as to grip against the internal surface 55 of the sleeve 67. An expansion spring 84 is disposed between said wedges to roll them up the inclinations of the cam surface 81-81a so that said wedges both grip against the internal surface of the sleeve 67 to hold both sleeves against 60 relative movement in either direction.

To actuate said rolling wedges to permit either the extension or contraction of the sleeves 66-67, the following is provided: a clevis or yoke 85 is disposed in the tube with its cross bar at 65 one end thereof engaged with the wedge 82 and with its other ends operatively connected to a pair of links 86 that extend out through the outer end of the sleeve 66. A second pair of links 87 is also arranged in said outer end of 70 said sleeve and carries an abutment 88 at its inner end to engage against the wedge 82a. The outer ends of the links 86-87 are pivotally connected to the opposed arms of a double arm trigger 89 that is also pivoted on the pin 71 before 75 mentioned.

When the trigger 89 is swung in a counter-clockwise direction as viewed as in Fig. 3, it is apparent that a push is imparted to the links 87 and a pull is imparted to the links 86. This causes a movement of the wedges 82-82a toward each other so as to roll down the surfaces 81-81a to compress the spring 84 between them. As the wedges roll down the surfaces 81-81a, they release their grip on the internal surface of the sleeve 67 so that the sleeves 66-67 are relatively extensible or contractile as desired to provide the necessary length of the fulcrum bar for adjusting the position of the chin rest or engageable means 59. When pressure on the trigger 89 is released, the spring 84 expands to return 10 the wedges upwardly of the cam surfaces 81-81a to again grip against the internal surfaces of the sleeve 67 to lock it to the sleeve 66.

The chin engageable means or member 59 is capable of a turning adjustment about the pin 20 71 as an axis and this adjustment is accomplished by the following mechanism. The chin engageable member 59 is provided with side-arms 90-90 that straddle the head 60 and the pin 71 before mentioned also extends through 25 said arms not only to hold them against displacement, but also to provide the pivotal axis therefor. The head 60 of the actuating bar 61 is made with a segmental gear section 91 and this gear section is engaged by a worm 92 that 30 is rotatively mounted as at 93 with respect to a post-like portion 94 that connects the two arms of the chin engageable member together. It is apparent that by turning the worm 92, the chin engageable member is caused to turn about the 35 pin 71 as an axis to move the said member into the desired angular position with respect to the head 60.

In the use of the mask, it is applied in the usual manner, with the forehead engaged with the rest 40 14 and the strap or stall 15 engaged upon the back of the head. This arranges the eyes of the wearer into the plane of the sight opening 27. The wearer, while holding the grip 22 with one hand, reaches up under the bottom of the hood and grasps the two triggers 80 and 89 and pinches them together. This releases the clutch mechanism in both the actuating bar and in the fulcrum bar. Simultaneously with this movement of the triggers, the fulcrum bar and the actuating 50 bar are swung upwardly about the axis pins 45 47 and 57 into a position wherein the member 59 engages the chin.

When the triggers are released, the fulcrum bar locks itself and holds the parts in this approximate position. The worm 92 is then turned to swing the member 59 about the pin 71 so that the chin firmly engages in the hollow or recess of 55 said member 59.

The hand holding the grip 22 may now be released as the head is so engaged between the rest 14, stall 15 and member 59 that the mask snugly, yet comfortably, fits the wearer's head so that it requires no holding by hand. By reason of the formation and the adjustment of the member 59, the mask fits so perfectly that it does not drop away or toward the face when the head is positioned to look downwardly or upwardly.

In welding, the ray filtering member 36 protects the eyes from the harmful rays of the arc 70 when electric welding or from the flame when gas welding or burning. Assume that the operator desires a better sight of the work at hand to see how the same is progressing. When the arc or flame is removed from the work, the operator 75

moves his chin downwardly. This swings the chin engageable member about the axis 47 for the fulcrum bar and exerts a pull on the actuating bar 61 which is locked against extension by the wedge 73. By means of said pull on said bar, the bell crank lever 51 is swung counterclockwise about its axis 51. This acts through the arm 55 not only to force the tube 48 downwardly on the plunger 46 to compress the spring 52, but it exerts a pull on the link 49 which through the arm 51 swings the frame for the ray filter inwardly and downwardly to engage against the stop 43 to uncover the opening 27. The operator then peers through the protecting glass 28 for a full vision of the work at hand.

To again cover the sight opening with the ray filter, the lower jaw of the operator is merely closed against the upper jaw. This releases the pressure on the member 59 when the spring 52 expands to return all parts to their normal position. In the movement of the parts, the plunger means 45 swings about the pin 47 as an axis to accommodate the swinging movement of the related parts such as the bell crank lever 54 and link 49.

It is apparent from the matter above set forth that the mask is capable of being adjusted to fit the features of the operator, so efficiently that no hands are required to hold the mask in place, no matter what angular position the head must take, to accommodate the work being done. Thus, both hands are left free so that one hand may be used for holding on to adjacent structure, such as when the operator is working under precarious conditions.

By reason of the adjustments provided for in the actuating bar and fulcrum bar, as well as by the angular adjustment of the means 59 with respect to the connected together ends of the said bars, the chin engageable means is capable of adjustment to fit any kind or size of facial features.

While in describing the invention, I have referred in detail to the form, arrangement and construction of the various parts involved, the same is to be considered only in an illustrative sense so that I do not wish to be limited thereto except as may be specifically set forth in the appended claims.

I claim as my invention:

1. In a welder's mask, means adapted to be worn upon the head of a person and having a sight opening therein, means providing a ray filter mounted for movement to cover and uncover said opening, chin engageable means, means connecting said chin engageable means with said ray filter means for moving the latter to cover and uncover the sight opening, and means providing for an adjustable pivotal mounting for said chin engageable means on said connecting means and comprising a gear segment carried by said connecting means and a worm carried by said chin engageable means and engaged with said gear segment.

2. In a welder's mask, means adapted to be worn upon the head of a person and having a sight opening therein, means providing a ray filter mounted for movement to cover and uncover said opening, chin engageable means, means connecting said chin engageable means with said ray filter means for moving the latter to cover and uncover the sight opening, said connecting means including parts capable of relative movement for adjustment to provide an upward and downward movement of said chin

engageable means as well as a movement of said means toward and away from said first mentioned means, and means providing an adjustable pivotal mounting for said chin engageable means on said connecting means, said means including a gear segment carried by said connecting means and a worm carried by said chin engageable means and engaged with said segment.

3. In a welder's mask, means adapted to be worn upon the head of a person and having a sight opening therein, means providing a ray filter normally covering the sight opening, means providing a pivotal axis for the bottom portion of said ray filter means and about which said means may swing inwardly and downwardly to uncover the sight opening, chin engageable means, means connecting said chin engageable means with said ray filter means for moving the latter to cover and uncover the sight opening, means for adjusting said chin engageable means upwardly and downwardly, as well as toward and away from the first mentioned means, and means providing an adjustable pivotal movement of said chin engageable means on said connecting means.

4. In a welder's mask, means adapted to be worn upon the head of a person and having a sight opening therein, means providing a ray filter normally covering the sight opening, means providing a pivotal axis for the bottom portion of said ray filter means and about which said means may swing inwardly and downwardly to uncover the sight opening, chin engageable means, means connecting said chin engageable means with said ray filter means for imparting a swinging movement to the latter to cover and uncover the sight opening, said connecting means including parts capable of relative movement for adjustment to provide an upward and downward, as well as an inward and outward movement of the chin engageable means into the desired position, means for holding said parts of said connecting means in the desired adjusted position and manually operative means carried by said connecting means for releasing said holding means.

5. In a welder's mask, means adapted to be worn upon the head of a person and having a sight opening therein, means providing a ray filter mounted for movement to cover and uncover said opening, chin engageable means, a fulcrum bar pivotally connected to the first mentioned means, an actuating bar cooperating at one end with one end of said fulcrum bar for carrying said chin engageable means, and means operatively connecting the other end of said actuating bar to said fulcrum bar and to said ray filter means respectively for moving the latter with respect to said opening when said chin engageable means is actuated, said chin engageable means being pivotally mounted on said connecting means and which carries a gear segment, and a worm carried by said chin engageable means and meshing with said gear segment to adjust the chin engageable means upon its pivotal mounting.

6. In a welder's mask, means adapted to be worn upon the head of a person and having a sight opening therein, means providing a ray filter mounted for movement to cover and uncover said opening, chin engageable means, a fulcrum bar comprising a plurality of telescopic members, one pivotally connected to the first mentioned means and another carrying said

chin engageable means, and means operatively connected to one of said members of said fulcrum bar and to said ray filter means respectively for moving the latter with respect to said opening when said chin engageable means is actuated.

7. In a welder's mask, means adapted to be worn upon the head of a person and having a sight opening therein, means providing a ray filter mounted for movement to cover and uncover said opening, chin engageable means, a fulcrum bar pivotally connected to said first mentioned means for a swinging movement, means providing a pivotal adjustment of the chin engageable means upon said fulcrum bar, and means connected to said fulcrum bar and to said ray filter means respectively for moving the latter with respect to said opening when said chin engageable means is actuated.

8. In a welder's mask, means adapted to be worn upon the head of a person and having a sight opening therein, means providing a ray filter mounted for movement to cover and uncover said opening, a chin engageable member, means providing a fulcrum bar pivotally connected at one end to said first mentioned means, means providing an actuating bar operatively connected at one end with respect to said ray filter means and operatively connected at the other end to the other end of said fulcrum bar, and means for operatively mounting said chin engageable means with respect to the last mentioned end of said fulcrum bar and said actuating bar respectively.

9. In a welder's mask, means adapted to be worn upon the head of a person and having a sight opening therein, means providing a ray filter mounted for movement to cover and uncover said opening, a chin engageable member, means providing a fulcrum bar pivotally connected at one end to said first mentioned means, means providing a telescopically adjustable ac-

tuating bar operatively connected at one end to said ray filter means and operatively connected at the other end to the other end of said fulcrum bar, and means for operatively mounting said chin engageable means with respect to the last 5 mentioned end of the fulcrum bar and said actuating bar respectively.

10. In a welder's mask, means adapted to be worn upon the head of a person and having a sight opening therein, means providing a ray 10 filter mounted for movement to cover and uncover said opening, a chin engageable member, means providing a fulcrum bar pivotally connected at one end to said first mentioned means, means providing a telescopically adjustable actuating bar operatively connected at one end to said ray filter means and operatively connected at the other end to the other end of said fulcrum bar, means for releasably securing said fulcrum bar and said actuating bar respectively in their 20 desired adjusted condition as to length, and means for operatively mounting said chin engageable means with respect to the last mentioned end of the fulcrum bar and said actuating bar respectively. 25

11. In a welder's mask, means adapted to be worn upon the head of a person and having a sight opening therein, means providing a ray filter mounted for movement to cover and uncover said opening, a chin engageable member, 30 means providing a fulcrum bar pivotally connected at one end to said first mentioned means, means providing a telescopically adjustable actuating bar operatively connected at one end to said ray filter means and operatively connected at the other end to the other end of said fulcrum bar, and means providing a pivotal adjustable mounting for said chin engageable means with respect to the last mentioned end of the fulcrum bar and the said actuating bar respec- 35 tively. 40

KAISER W. MENTETSKI.
